UNITED STATES PATENT OFFICE.

DUNCAN A. McCONNELL, OF ARLINGTON, NEW JERSEY, ASSIGNOR TO LOVELL-McCONNELL MANUFACTURING COMPANY, OF NEWARK, NEW JERSEY, A CORPORATION OF DELAWARE.

HAND-OPERATED HORN.

1,288,080.

Specification of Letters Patent. Patented Dec. 17, 1918.

Application filed April 24, 1915. Serial No. 23,547.

To all whom it may concern:

Be it known that I, DUNCAN A. McCONNELL, a citizen of the United States, and resident of Arlington, in the county of Hudson and State of New Jersey, have invented certain new and useful Improvements in Hand-Operated Horns, of which the following is a specification.

My present invention was designed primarily as an improvement in my prior hand operated horn shown in my Patent No. 1,232,583 (application filed December 8th, 1914) but certain features of the invention are applicable to specifically different horns of the same type, as for instance, those shown in Patents Nos. 1,090,080, applied for September 30, 1910, 1,153,534, applied for September 22, 1914, 1,180,524, applied for February 9, 1914, 1,226,049, applied for December 16, 1910, 1,232,579, applied for December 29, 1910, 1,239,426, applied for October 12, 1915 and 1,242,957, applied for August 23, 1913.

Horns of this type are operated by pushing upon a plunger provided with a rack bar engaging a pinion adapted to drive a rotor provided with projections adapted to vibrate a diaphragm to produce the desired sound. The plunger is returned to initial position by means of a spring and the mechanism is provided with a ratchet or other slip connection so that the return movement of the plunger does not reverse the direction of rotation of the cam.

In all of these horns, the plunger reciprocates at right angles to the axis of the horn, and since, under normal conditions, the axis of the horn must be horizontal in order to project the sound horizontally, it has been the usual practice to arrange the plunger to reciprocate vertically through the top of the casing and to operate it by downward pressure of the hand. This down stroke operation is assisted by gravity and for this reason has been universally adapted in horns of this type, one maker following another without giving further thought to the subject. I have discovered, however, that in actual practice this arrangement has objections which can be avoided by my present invention.

One objection is that in ordinary practi-

cal use of these devices, it frequently occurs that the weight of the hand even assisted by considerable muscular pressure is insufficient to start rotation of the mechanism, as for instance, where the mechanism is permitted to become rusty, dirty or unoiled or where the rotor happens to stop with one of the inclined or ratchet faces wedged against the wearpiece on the diaphragm.

Moreover, it is characteristic even of well oiled instruments that they require far more power to start them and force the first tooth of the rotor past the diaphragm projection than is required to keep them going after they are once started. Hence, in practice, the operator in order to be certain of producing an emergency warning signal, must always strike the plunger a blow powerful enough to certainly operate it even if the rotor does happen to be wedged or the operating mechanism disordered. In this situation, I have discovered that in the case of the vertical plunger, the power available by transverse downward movement of the hand and forearm pivoting at the elbow, is frequently ineffective even though assisted by gravity. Moreover, the muscular effort required to continue the downward movement of the plunger with accelerating velocity is also at a disadvantage because in practice it is applied transversely of the forearm and with the well known disadvantageous extensor leverage of the elbow.

I have discovered that by utilizing the endwise momentum of the forearm instead of the gravity stroke of the hand, together with the advantageous muscular leverage of the shoulder, enormously greater power, fully adequate to all conditions can be applied with almost no conscious effort on the part of the operator.

Another objection to the vertical plunger is that the natural downward curl of the fingers of the operator naturally bring them in contact with the top of the case before the down stroke is completed, thereby shortening the stroke and injuring the fingers. Increasing the vertical height of the plunger enough to prevent this, is so objectionable for other reasons that it is never attempted in practice. I have obviated this difficulty by arranging the plunger in a position where

the fingers will not contact with the case even if crooked to or beyond a right angle to the palm of the hand.

Another objection is that these plungers 5 seldom fit the slide opening in the casing with sufficient accuracy to make a water tight joint, and where the opening is in a top surface of the casing, water falling on the horn either during rain or washing of the vehicle, 10 finds its way by gravity into the interior of the casing. I avoid this objection simultaneously with the others, by arranging the plunger and its slide opening horizontally in a vertical wall of the casing.

15 One object of my invention is to obviate all of the above difficulties and to secure the above advantages by reorganizing the operative mechanism so that while maintaining the required relation of the actuating rotor 20 to its diaphragm, I may at the same time arrange the rack bar plunger parallel with the axis of the horn and projecting horizontally through the vertical rear wall of the case, preferably well above the horizontal diameter 25 of said wall and preferably near enough to the periphery so that crooked fingers will pass freely above the casing but preferably not so near but that the hand-engaging piece on the plunger will be rearwardly within the 30 projected area of said end wall. Thus arranged there is no opportunity for water to flow by gravity through the plunger slide opening; the operator has the advantage that the blow being horizontal and delivered with 35 the forearm substantially in alignment with the direction of the blow, the initial impact of his hand has behind it the entire endwise momentum of his forearm instead of the transverse momentum of the hand alone; the 40 follow-up effort required to accelerate the movement of the plunger to high speed, is the easy powerful movement similar to what is known as the "short arm jab" of the boxer or pugilist; and there will be no possibility 45 of crooked fingers being injured or preventing a full stroke of the plunger. In actual practice, the momentum advantage and the power advantage are both so great that very little conscious effort is required to operate 50 my horizontal plunger even when the mechanism is unoiled or badly worn.

A further object of my invention is to reduced the size of the casing and increase the size of the rotor substantially to their limits 55 so that both the diameter and length of the casing may be only slightly greater than the diameter of the rotor. Various attempts have been made to secure this desired large size of rotor and small size of casing, but if 60 the rotor be mounted in the plane of a diameter of the casing, the reciprocating member has come either at one side of a vertical diameter or has come in the rear of the back edge of the rotor. The first is objectionable 65 because of the non-cylindrical appearance

and the tendency to twist or loosen the horn when pressure is applied to the plunger in sounding it, and the latter necessitates an objectionable increase in the length of the casing. By means of my invention, I am 70 able to secure a rotor of the largest possible diameter mounted in the plane of a diameter of the casing, which casing is of substantially the same length as the diameter of the rotor, and at the same time the reciprocating 75 plunger member lies in the vertical plane of the axis of the horn.

The preferred embodiment of my invention includes various features of importance which will be set forth more fully herein- 80 after and more particularly pointed out in the claims, but among these are the arrangement of parts whereby the rotor and the multiplying gearing may be adjusted toward and from the diaphragm without disturbing 85 the operative relationship of the reciprocating member and without necessitating any increase in the size of the opening in the casing and through which the said reciprocating member moves.

90 The rotor and multiplying gearing are preferably carried by a bracket suspended from and adjustable along the top wall of the casing, and another important feature of my invention resides in the means employed 95 for transmitting to the end wall of the casing the strain imparted to the said member. The said bracket is preferably of cast metal, and as a further important feature of my invention, I so design the parts that this 100 casting serves not only as a support for the rotary and reciprocating members, but also serves as an oil cup for the lubrication of the movable parts.

105 As a further important feature of my invention, I limit the normal outward movement of the reciprocating member by a stop preferably threaded into the end of said member and hold the reciprocating member in its outer limiting position by a spring abutting directly against this stop and thus normally tending to prevent the stop from becoming unscrewed.

110 These various features, together with others hereinafter pointed out, may be, and preferably are, all incorporated in one construction although certain of them may be used independently of others.

115 In the accompanying drawings, to which reference is to be had and in which reference characters indicate corresponding parts in the several views, I have shown one such embodiment although it is of course understood that this is merely illustrative and that various changes may be made within the spirit of my invention and without departing from the scope of the appended claims. In these drawings,

120 Figure 1 is a side elevation of a horn constructed in accordance with my invention, a 125

portion of the casing and of the supporting bracket being broken away;

Fig. 2 is a transverse section on the line 2-2 of Fig. 1;

Fig. 3 is a transverse section on the line 3-3 of Fig. 1, and

Fig. 4 is a longitudinal section on the broken line 4-4 of Fig. 2.

In the specific form illustrated, I employ a diaphragm 10 clamped about its periphery between parallel annular flanges on front and rear diaphragm casing members 11 and 12, the said flanges being preferably spaced from the diaphragm by thin washers of cork, pasteboard or other suitable material and held in the desired assembled relationship by an annular series of bolts or screws 13. The front diaphragm casing 11 has a large central opening at which is secured the base of the resonator 14, and the diaphragm has at its center a suitable wear-piece 15 with which the diaphragm vibrating mechanism engages. The rear casing member 12 is in the form of a sheet metal cup having a cylindrical wall 16 formed integral with the diaphragm clamping flange at one end and integral with a rear end wall 17 at the opposite end. This cup-shaped casing is thus closed at its open end by the diaphragm and incloses a chamber within which the diaphragm vibrating mechanism is supported. The general arrangement of parts so far described has been employed heretofore in other forms of horns.

For supporting the operating parts, I provide a cast metal bracket member 18 and suspend this from the upper side of the peripheral wall of the casing. The supporting and suspending means is preferably in the form of two screws 19, 19, threaded into the upper side of the bracket and extending through openings or slots in the peripheral wall of slightly greater length than the diameter of the screws but smaller than the screw heads so that the said openings are always covered by the screw heads but the bracket may be adjusted to a limited extent lengthwise of the casing and toward and from the diaphragm. The bracket has a cylindrical extension 20 projecting through an opening in the end wall 17 at a point in the vertical diameter above the center of the casing and approximately midway between the center and the peripheral wall. This extension or boss has a horizontal passage therethrough to receive the reciprocating actuating member 21 and permits of the latter moving back and forth in a direction at an angle to the plane of the diaphragm. In order to effectively support the bracket, resist the tendency to move toward the diaphragm under the strain of a pressure on the actuating member, and to form a substantially air-tight closure, I provide a nut 22 which is not only interiorly threaded to

screw on the extension or boss 20, but also exteriorly threaded to screw into the aperture in the end wall. The interior and exterior threads on this nut are of different pitch so that when screwed in or out, the bracket 70 and rotor are adjusted to or from the diaphragm an amount equal to the difference in pitch of the two threads. When the two clamping screws 19, 19, are tightened, the nut will automatically become locked and 75 thus no lock nut or other locking means need be employed. The nut preferably has an outer milled or non-cylindrical end by means of which it may be tightened to the desired extent.

The reciprocating plunger member 21 is, as previously indicated, mounted in the plane of the vertical diameter of the casing and the wear-piece on the diaphragm is also in this same plane. For vibrating the diaphragm, I provide a rotor 24 having a peripheral series of cams, teeth, or projections, for engagement with the wear-piece. This rotor is of a diameter closely approximating the internal diameter of the casing and its 90 plane of rotation substantially coincides, with a diametric plane of the casing. In order to bring the rotor into the proper position in respect to the wear-piece, I screw the parts so that the center of the rotor 95 comes directly below the axis of the reciprocating actuating member, and in the longitudinal axis of the casing. The rotor is mounted on a shaft 25, parallel to the diaphragm, but at an angle to the horizontal 100 as is clearly indicated in Fig. 2.

The shaft 25 is journaled in the bracket 18 and is held against endwise movement in any suitable manner. Preferably there is provided a bushing 26 at the higher end 105 of the shaft and this end is threaded and receives a suitable washer and nut, or pair of nuts, or other retaining means. The rotor is mounted upon the lower end of the shaft and is preferably dished toward the bracket, and is rigidly secured to a collar 27 of greater length than the thickness of the washer and of a length corresponding to the amount of dishing of the rotor so as to provide a bearing of suitable length and prevent tendency of the rotor to wobble as the bearing wears. The collar and rotor are free to rotate in one direction in respect to the shaft, rotation in the opposite direction being prevented by a spring-pressed pawl 28 110 carried by the face of the rotor and engaging with a ratchet wheel 29 mounted on the lower end of the shaft and locked against rotation in respect to the latter.

For rotating the shaft upon a reciprocation of the actuating member 21, I provide the said actuating member with teeth 30 so that the latter constitutes a rack bar and provide the shaft 25 with a series of grooves 31 converting the latter into a pinion. Pref- 125

erably I secure an increased speed of the rotor in respect to a given movement of the actuating member by providing an interposed member including a pinion 34 meshing with 5 the rack bar and a larger pinion or gear wheel 35 rigid with the pinion 34 and meshing with the pinion 31. For economy in manufacture and to simplify the assembling, the pinion 34 may be formed from a section 10 of a bar provided with a peripheral series of longitudinally extending grooves and drilled to receive and rotate upon a shaft 36 in the form of a screw supported at both ends in the bracket and threaded at one end 15 to hold it in place. The gear 35 may be driven on to one end of this bar section and slightly swaged or distorted to prevent it from rotating in respect to the bar section constituting the pinion, as is clearly shown 20 in Figs. 1 and 3. By means of this mechanism, an inward endwise movement of the actuating member 21 transmits power to the rotor to rotate the latter in one direction through the medium of the other parts 34, 25 35, 31, 29 and 28. The actuating member 30 may return without a return rotation of the rotor by a slipping of the pawl over the ratchet wheel 29. This rack bar is shown as being square in cross section so as to be 35 prevented from rotation about its own axis and so as to hold the teeth at all times in proper relationship with the pinion with which it engages. It is of course evident that any other means might be provided for preventing the rotation of the rack bar.

To facilitate the return movement of the actuating member and to limit this return movement, I provide a stop in the form of a screw 40 threaded into the end of the 40 actuating member and of larger diameter than said member and adapted to abut against the shoulder of the bracket. A coil 45 spring 41 in axial alignment with the actuating member abuts against this screw and continually tends to force the actuating member outwardly. The spring is inclosed within a tubular casing member 42 which is spirally threaded and screwed into the bracket so as to be rigid with the latter. 50 An outer end wall, or any other suitable stop at the end of this tubular casing adjacent to the diaphragm, may support and retain the other end of the spring. The screw 40 cannot become disengaged from the reciprocating member without moving toward 55 the spring and against the tension of the latter and therefore the spring not only serves to return the reciprocating member, but prevents the screw or stop 40 from 60 loosening.

To facilitate the lubrication of the parts, the bracket which, as previously stated, is in the form of a casting, has an oil chamber 45 in the upper side thereof directly beneath the top wall of the casing and closed

by the latter. Oil passages 46 and 47 lead from this chamber to points adjacent the bearings of the rotating parts. Oil may be admitted to the oil chamber 45 through an oil inlet normally closed by any suitable 70 form of valve 48.

The horn may be secured to a vehicle or to any other supporting structure by various brackets heretofore employed although preferably I employ the specific bracket shown 75 which includes a metal strap bent to substantially U-shape and having a base 50 and upturned ends 51 and 52. One of these ends may be secured to the diaphragm clamping portion by the same bolts or screws which 80 hold the diaphragm casing parts together, or by separate bolts or screws, while the other upturned end 52 may be fastened to the end wall 17 of the casing by a suitable bolt or screw 53. The base member 50 may 85 be secured to the supporting structure in any suitable manner, not shown, and may be either flat, curved, or otherwise bent, to correspond to the surface of the supporting structure. 90

When used for the primary purpose for which it was originally invented, namely as a warning signal on automobiles, trucks, etc., it should be secured with its axis horizontal and its mouth-piece forwardly directed. In such position, it will have all 95 of the advantages first above mentioned but it is obvious that it may be secured to supports other than vehicles and may be used for purposes other than warning and may 100 be secured in position other than that for which it was designed, such other uses and positions involving only sacrifice of some of the said advantages.

In whatever position used, the instrument 105 as a whole will be substantially immune from ordinary blows directed lengthwise of the instrument, as contrasted with the old instrument in which lengthwise movements catch the plunger transversely, while transverse movements catch the mouth-piece or resonator transversely. 110

Having thus described my invention, what I claim as new and desire to secure by Letters Patent is: 115

1. An alarm or signaling device including a diaphragm, a casing extending rearwardly thereof, including a peripheral wall parallel with the axis of the diaphragm and a vertical end wall, in combination with manually actuated means for mechanically vibrating said diaphragm, said means including a rotor provided with diaphragm engaging projections, a plunger reciprocating substantially lengthwise of the device, extending rearwardly through said vertical end wall and provided at its rear end with an exterior hand piece whereby it may be manually forced forward toward the diaphragm, a spring for returning the plunger 120 125 130

- to initial position and means for applying the manually-forced, forward movement of the plunger to revolve said rotor, the location and size of the parts being such that
- 5 said hand piece lies wholly within the rearwardly projected cross section of said peripheral wall.
2. An alarm or signaling device including a diaphragm, a casing extending rearwardly thereof, including a peripheral wall parallel with the axis of the diaphragm and a vertical end wall, in combination with manually actuated means for mechanically vibrating said diaphragm, said means including a rotor provided with diaphragm engaging projections, a plunger reciprocating substantially lengthwise of the device extending rearwardly through said vertical end wall and provided at its rear end with
- 10 an exterior hand piece whereby it may be manually forced forward toward the diaphragm, a spring for returning the plunger to initial position and means for applying the manually-forced, forward movement of
- 15 the plunger to revolve said rotor, the location and size of the parts being such that a peripheral edge of said hand piece is approximately in alinement with said peripheral wall while the remainder of said
- 20 handpiece lies wholly within the rearwardly projected cross section of said peripheral wall.
3. An alarm or signaling device including a diaphragm, a casing extending rearwardly thereof, including a peripheral wall parallel with the axis of the diaphragm and a vertical end wall, in combination with manually actuated means for mechanically vibrating said diaphragm, said means including a rotor provided with diaphragm engaging projections, a reciprocating plunger in operative relation with said rotor, extending through said rear wall substantially parallel with said axis but adjacent to said peripheral wall on the upper side above said bracket.
4. An alarm or signaling device including a diaphragm, a casing extending rearwardly thereof, including a peripheral wall parallel with the axis of the diaphragm and a vertical end wall, in combination with manually actuated means for mechanically vibrating said diaphragm, said means including a rotor located within the casing and provided with diaphragm engaging projections, a reciprocating plunger located eccentric to but reciprocating approximately parallel with said axis and said peripheral wall and extending through said vertical rear wall at right angles thereto and provided at its rear end with an exterior handpiece whereby it may be manually forced forward toward the diaphragm, a spring for returning the plunger to initial position, and means for applying the manually-forced, forward movement of the plunger to revolve said rotor, together with means for mounting said device with its axis horizontal and said hand piece rearwardly directed with its upper edge in approximate alinement with an upper portion of said peripheral wall.
5. An alarm or signaling device including a vibratory sound producing member, a substantially cylindrical casing secured thereto, a rotor within said casing and disposed substantially in an inclined diametrical plane of said casing, an actuating member extending into said casing through the end wall thereof and movable toward and from the diaphragm with its axis disposed in the same vertical diametrical plane of said casing, with a diameter of said rotor normal to said diaphragm, and power transmitting mechanism for rotating said rotor upon the movement of said actuating member.
6. An alarm or signaling device including a diaphragm, a casing secured thereto and including a peripheral wall and an end

- wall, a bracket secured to the peripheral wall and adjustable toward and from said diaphragm, a rotor carried by said bracket for vibrating said diaphragm, a rack bar movable through said end wall for rotating said rotor, and means for securing said bracket to said end wall, said means including a threaded boss projecting from said bracket toward said end wall and a collar internally threaded on said boss and externally threaded within said end wall.
9. An alarm or signaling device including a diaphragm, a casing including a peripheral wall and an end wall, a bracket secured to the peripheral wall and adjustable toward and from said diaphragm, a rotor carried by said bracket for vibrating said diaphragm, a rack bar movable through said end wall for rotating said rotor, and means for securing said bracket to said end wall, said means including a threaded boss integral with said bracket and projecting through said end wall and a collar internally threaded on said boss and externally threaded within said end wall, the threads upon the interior and exterior of said collar being of different pitch.
10. An alarm or signaling device, including a diaphragm, a casing including a peripheral wall and an end wall, a bracket secured to one of said walls and having an externally threaded boss projecting through the other wall, an externally and internally threaded nut mounted on said boss and engaging with said last mentioned wall, a rotor within said casing for vibrating said diaphragm, an actuating member extending through said boss, and power transmitting mechanism for rotating said rotor upon an endwise movement of said actuating member.
11. An alarm or signaling device including a diaphragm, a casing secured thereto, a bracket within said casing, a shaft carried by said bracket, a rotor carried by said shaft for vibrating said diaphragm, a rack bar movable endwise toward said diaphragm, and supported by said bracket, a stop carried by said rack bar for limiting the endwise movement of said rack bar, and a spring for forcing said rack bar in one direction.
12. An alarm or signaling device including a diaphragm, a casing secured thereto, a bracket within said casing, a shaft carried by said bracket, a rotor carried by said shaft for vibrating said diaphragm, a rack bar movable endwise toward said diaphragm, and supported by said bracket, a stop carried by said rack bar for limiting the endwise movement of said rack bar, and a spring for forcing said rack bar in one direction, said spring being disposed in axial alignment with said rack bar and engaging with said stop.
13. An alarm or signaling device including a diaphragm, a casing secured thereto, a bracket within said casing, a shaft carried by said bracket, a rotor carried by said shaft for vibrating said diaphragm, a rack bar movable endwise toward said diaphragm, and supported by said bracket, a stop carried by said rack bar for limiting the endwise movement of said rack bar, a spring for forcing said rack bar in one direction, and a tubular casing secured to said bracket and inclosing said spring and projecting toward said diaphragm.
14. An alarm or signaling device including a diaphragm, a casing secured thereto, a bracket within said casing and supported from the upper wall thereof, a rack bar projecting through the wall of the casing and guided by said bracket, a spring for normally forcing said rack bar in one direction, a tubular casing within said first mentioned casing and inclosing said spring and secured to said bracket, and means for vibrating said diaphragm upon the movement of said rack bar in one direction.

Signed at Newark, in the county of Essex and State of New Jersey, this 22nd day of April, A. D. 1915.
